DESIGN FOR A HANDBAG

Irving Kaplan, Bronx, N. Y.

Application January 27, 1941, Serial No. 98,389

Term of patent 7 years

To all whom it may concern:

Be it known that I, Irving Kaplan, a citizen of the United States and resident of the Bronx, New York, in the county of Bronx and State of New York, have invented a new, original, and ornamental Design for a Handbag, of which the following is a specification, reference being had to the accompanying drawing, forming a part thereof, and of which Figure 1 is a view in front elevation of a handbag showing my new design, Fig. 2 is a view thereof in end elevation, and Fig. 3 is a fragmentary sectional view showing

the ribs as they appear throughout the sides of the handbag.

The rear view of the handbag is the same as the front.

The characteristic features of my design for a handbag reside in the raised ornamentation on the sides of the bag having the configuration and arrangement shown.

I claim:

The ornamental design for a handbag, substantially as shown and described.

IRVING KAPLAN,
